United States Patent

Des. 241,313

Patented Sept. 7, 1976

241,313

SIGN HOLDER OR THE LIKE

David L. McLintock, Jacksonville, Fla., assignor to Simple Signman Systems, Inc., Jacksonville, Fla.

Filed Dec. 15, 1975, Ser. No. 640,951

Term of patent 14 years

Int. Cl. D8—08

U.S. Cl. D8—245

FIG. 1

FIG. 4

FIG. 2

FIG. 5

FIG. 3

FIG. 6

FIG. 1 is a top view of the sign holder or the like showing my new design;

FIG. 2 is a front elevational view thereof, with one flange being broken away for clarity of illustration;

FIG. 3 is a bottom view thereof;

FIG. 4 is a right side elevational view thereof;

FIG. 5 is a cross-sectional view taken along line 5—5 of FIG. 1; and

FIG. 6 is a cross-sectional view taken along line 6—6 of FIG. 1.

I claim:

The ornamental design for a sign holder or the like, substantially as shown.
